UNITED STATES PATENT OFFICE

ISRAEL MORDECAI RABINOWITCH, OF MONTREAL, QUEBEC, CANADA, ASSIGNOR TO
THE MONTREAL GENERAL HOSPITAL, OF MONTREAL, CANADA

APPARATUS FOR DIAGNOSING HUMAN AILMENTS

Application filed July 6, 1926. Serial No. 120,846.

My invention relates particularly to the determining of metabolism, and has particular reference to the diagnosis of diseases of the thyroid gland. Heretofore in order to arrive at the rate of metabolism it has been necessary to follow through more or less complex chemical and physical tests, and, additionally, these methods heretofore used were relatively slow and required in some cases a high degree of technical skill for the analysis of the respiration breath. The object of my invention is to overcome these defects and simplify the obtaining of the rate of metabolism, and also eliminate all technical skill, and at the same time automatically analyze the respirations and record the result.

To this end my invention consists, broadly speaking, of the combination with a valvular respirator, of a respiration member, a chamber for receiving respirations from the respiration member, an atmospheric air chamber, electric circuit including a Wheatstone bridge and a galvanometer, with preferably a supplemental recording galvanometer, the respective legs of the Wheatstone bridge including the respective chambers and thereby acting as a couple to operate the galvanometer or galvanometers.

For full comprehension, however, of my invention reference must be had to the accompanying drawings in which similar reference characters indicate the same parts and wherein:

Figure 1 is a perspective view of a portable case in which the apparatus constituting the present invention is carried;

Figure 2 is a horizontal sectional view taken on line 2—2 Figure 5 illustrating the electric mechanism for operating the galvanometer for instant reading and a recording galvanometer;

Figure 3 is a horizontal sectional view taken on line 3—3 Figure 5;

Figure 4 is a similar sectional view taken on line 4—4 Figure 5;

Figure 5 is a vertical sectional view taken on line 5—5 Figure 2 and illustrating the connections for the respiration member;

Figure 6 illustrates in elevation the valvular respirator and its pipe connections;

Figure 7 is a diagrammatic illustration of the electric circuits; and

Figure 8 is a perspective view illustrating the invention in use.

The valvular respirator consists of a tubular member *b* carrying a mouthpiece and a pair of globular glass one-way valvular members *d* and *e*, the valve of member *d* checking flow towards the mouthpiece and permitting flow in the opposite direction, and the valvular member *e* checking flow from the mouthpiece and permitting flow towards the same. A pipe *f* conducts the exhalations to a coupling *g*, the port of which is the intake port of the respiration member *h* within the portable case, and registering dials *i* registering the volume of the exhalations. This portable case is divided into an upper chamber *k*, and a pair of parallel horizontal chambers 10 and 20 containing the electrical system for operating the electrical devices. There is also a main bottom chamber *m* containing the halitometer, a battery chamber *o* containing batteries *p*, a chamber *q* in which the valvular respirator is carried and a chamber *s* for the folding bracket *r*. The chamber 20 communicates with the atmosphere through pipe 20^b leading from an air chamber 20^a in open communication with the atmosphere through a gauze covered port 20^c. The respiration member consists in the main of a bellows-like diaphragm *h'* which is alternately expanded and shrunk by the pressure of the patient's exhalation. The movements of the diaphragm are transmitted through the arms *h*^a and gears *h*^b to and operate the recording dials. The galvanometer for instant reading is indicated at *t* and the recording galvanometer at *u* while a rheostat also included in the circuit is indicated at *v* and a switch at 100. The electrical system employed in a Wheatstone bridge illustrated in detail in Figure 7. It is energized by the battery *p* from one pole of which a wire 12 leads to a pair of branches 13 and 17 respectively the opposite terminals of which are connected to the terminals of a sub-circuit 14. The other pole of the battery is connected by a wire 16 to a pair of branches 15 and 18 respectively leading also to the terminals of the sub-circuit 14. The gal-

100

vanometer *t* is connected in shunt across the sub-circuit 14, and one limb of the latter preferably beyond the shunt connections, contains the recording galvanometer *u*, while the rheostat is included.

In the application of the apparatus to diagnose diseases of the thyroid gland the patient, usually in a reclining position, and having her nostrils blocked as at *w*, takes the respirator and breathes normally. The exhalations pass from the respirator through pipe α^a to the respiration member *h* and operate the latter, thus indicating the volume exhaled in a given time. The exhalations flow through the respiration member, pipe *y* and chamber 10 from which they flow through pipe 10^a to the atmosphere or otherwise as desired. In the meantime the current traverses the circuit as follows: From one pole of the battery along lead 12 to one side arm 13 of the Wheatstone bridge and energizes a sub-circuit 14 thus operating the two galvanometers, thence by leads 15—16, returning to the other pole of the battery. At the same time the other side of the Wheatstone bridge is operated by the circuit traversing the leads 12—17, the circuit 14 and lead 18, and returns to the battery by lead 16. In order to adjust this current the rheostat *v* is set in the usual way. Leads 13—15 have a portion parallel to each other and form one arm of the bridge. This arm is located in the chamber 10 through which the exhalations of the patient pass and parallel portions of the leads 17—18 form the other arm of the bridge, and this arm is in the chamber 20 which is in open communication with the atmosphere. An atmosphere containing carbon dioxide causes an electric conductor to vary in its resistance to the flow of an electric current proportionately to the degree of carbon dioxide contained in the atmosphere. Consequently the operation of the bridge in my apparatus and the fluctuation of the galvanometer are due to the fact that the arm 17—18 being in an atmosphere of pure air, the resistance of this arm to the flow of the electric current remains normal while the arm 13—15 being subjected to the exhalation flowing through the chamber 10 its resistance to the flow of the current in proportion to the carbon dioxide content of the exhalations.

The apparatus is connected up as follows:

The portable bracket consists of a pair of standards 25 and 25^a adapted to be fitted into tubular sockets 26 and 27 carried by the end of the case. The upper ends of these standards are formed to receive a horizontal rod 28 supported in position by these standards and a diagonal brace 29 hinged to the rod 28 and having its lower end seated in a cup-like socket 30, at the lower end of the case between the lower ends of the tubular sockets 27 and 28. The outer end of this

rod 28 has a pair of forked brackets 31 hinged thereto as at 32 and having its lower ends connected by ring hooks 33 to the globular valves *d* and *e* thus supporting the latter in proper position to have a patient receive the respirator *c*. The flexible tube *f* is then connected to the coupling *g*, the switch 100 is closed and the apparatus is ready for use. As the patient breathes inhalations are driven past the valve *e* and the exhaled breaths are drawn past valve *d* through the flexible tube *f* to and through the respiration member *h*. After the required interval, say fifteen minutes, the respiration member will have registered the volume of the exhalations on the recording dials of the respiration member, and the galvanometer will indicate the amount of carbon dioxide in the exhalations. The effect is that the variation in resistance being indicated on galvanometer *f*, and recorded on recording galvanometer *u*, the indications and recordings may be in calibrations of cubic centimeters of carbon dioxide. Consequently the volume of exhalations passing through the apparatus being indicated on the dials of the halitometer, the degree of carbon dioxide per cubic centimeter may be read at a glance on the galvanometer *f* and dials *i*. The result is that the rate of metabolism and the analysis of the exhalations are obtained without technical skill. Furthermore the apparatus being portable its use is not confined to hospitals but is available in private practice. The simplicity and inexpensiveness of the improved system makes it available to all practitioners and its use is equally efficient under all circumstances in the hands of persons of average intelligence.

What I claim is as follows:

1. An article of commerce consisting of a portable case with carrying handle and containing a respiration member, a pair of chambers, a Wheatstone bridge the arms of which are located in the respective chambers, a galvanometer within the electric circuit of the bridge, a rheostat for adjusting the electric circuit, a battery for energizing the circuit, a chamber in the case for containing an inhaler consisting of a mouth piece having a pair of oppositely extended branches, an outside air inhaler and containing a check valve allowing freedom of flow towards the inhaler, a tube means detachably connecting the other branch of the inhaler to the respiration member and containing a one-way valve allowing freedom of flow from the mouth piece to the respiration member; a second chamber containing a knock-down means for supporting the inhaler and the devices intimately connected thereto in position for use in the treatment of a subject.

2. An apparatus such as claimed in claim 1, the knock-down inhaler supporting means of which comprises a pair of tubular sockets

secured upon one end of the portable case, a pair of standards fitted into the socket, a horizontal rod supported at one end in the standards, a cup-like socket on the end of the case, a diagonal brace attached to and supporting the horizontal rod and seated in the cup-like socket, a pair of forked brackets hinged upon a hinged rod for supporting between them the inhaler and the devices intimately connected thereto in position for use in the treatment of a subject.

3. A portable apparatus for obtaining the basal metabolic rate of hyperthyroidism consisting of a case divided into compartments, one compartment containing a Wheatstone bridge and a galvanometer included in the bridge and a pair of chambers having the respective arms of the bridge threaded therethrough, one of such chambers being in communication with the atmosphere, a second compartment containing a respiration member mechanism and registering dials and having an inlet port and an outlet port, pipes connecting the outlet port of the respiration member to the other of the said chambers; a third compartment containing a battery with connections to the Wheatstone bridge; a fourth compartment containing an inhaler with lateral branches and having check valves in the branches; a fifth compartment containing a flexible tube for connecting one branch of the inhaler to the respiration member; and a sixth compartment containing a folding bracket for supporting the inhaler in position for use in the diagnosing of thyroidism.

4. An article of commerce consisting of a portable case with carrying handle and containing a respiration member, a pair of chambers, a Wheatstone bridge the arms of which are located in the respective chambers, a galvanometer within the electric circuit of the bridge, a rheostat for adjusting the electric circuit, a battery for energizing the circuit, a chamber in the case for containing an inhaler consisting of a mouth piece having a pair of oppositely extended branches, an outside air inhaler and containing a check valve allowing freedom of flow towards the inhaler, a tube means detachably connecting the other branch of the inhaler to the respiration member and containing a one-way valve allowing freedom of flow from the mouth piece to the respiration member, a second chamber containing a knock-down means for supporting the inhaler and the devices intimately connected thereto in position for use in the treatment of a subject.

In testimony whereof I have signed my name to this specification.
